No. 826,485.

PATENTED JULY 17, 1906.

G. W. DONNING.

ELECTRICAL TYPE WRITER SELECTING AND OPERATING MEANS.

APPLICATION FILED MAY 27, 1903.

UNITED STATES PATENT OFFICE.

GEORGE W. DONNING, OF EAST ORANGE, NEW JERSEY, ASSIGNOR TO
HARRY T. AMBROSE, OF ORANGE, NEW JERSEY.

ELECTRICAL TYPE-WRITER SELECTING AND OPERATING MEANS.

No. 826,485.

Specification of Letters Patent.

Patented July 17, 1906.

Application filed May 27, 1903. Serial No. 158,963.

To all whom it may concern:

Be it known that I, GEORGE W. DONNING, a citizen of the United States, residing at East Orange, in the county of Essex and State of New Jersey, have invented certain new and useful Improvements in Electrical Type-Writer Selecting and Operating Means; and I do hereby declare the following to be a full, clear, and exact description of the invention, such as will enable others skilled in the art to which it appertains to make and use the same.

The object of this invention is to provide an improved means for operating and controlling the writing mechanism for electrically-operated type-writing machines, and is to be distinguished from my copending application, filed of even date herewith, Serial No. 158,962, wherein the object is to provide a key mechanism that when depressed will first complete a circuit including a selecting-magnet and position a type-bar member and upon further depression will break said circuit and simultaneously close a circuit including a universal power-bar, thereby causing a type-bar corresponding to the key depressed to be operated and print a character.

In the present invention the object is to provide a key mechanism that will first complete a circuit including a selecting-magnet and position a type-bar member and upon further depression will break the circuit. Then upon still further depression it will make a circuit including a magnet that will operate a type-bar which has been positioned and cause it to print its character. When the member connected with the type-bar has been positioned, a suitable latch is caused to engage the member connected with the type-bar and retain it in position until engaged by the actuating-bar.

Another object is to provide an improved form of key or switch for controlling and operating such electrically-operated selecting and operating mechanism.

A further object is to provide a key mechanism which will effect a cycle of movement of operative parts as follows: first, electrical connection with a selecting-magnet to attract an armature-carrying pawl or lever that is suitably fulcrumed and which is thereby positioned for further operation; second, switching of the current from the said mag-

net to a second magnet to effect electrical connection with a magnet to attract the armature of an actuating power device, during which latter movement the pawl or lever is engaged by the power device, and the operative parts (that may be a type-bar or a type-head, a shifting actuator, or other operating part of a type-writer) are operated for a desired purpose, and, third, to break the circuit in order to cause return of the said parts to normal position, all upon the down movement of the key.

A further object is to provide novel constructions and arrangements for effecting these operations.

A further object is to provide a key construction which will when coöperating with an outside source of power and when operated perform several functions—namely, select, operate, permit return of the operated parts independently of the release of the key. The same may be employed to operate the typing and spacing and ribbon-feeding mechanism, another to shift the type-head, and another to shift the ribbon and other parts for operating any desired mechanism on the machine.

Another object is to provide a form of key that will first energize one of a set of selecting-magnets, then upon a further movement will cut out the said magnet, and upon a still further advance will energize a power-magnet, and upon a still further advance will cut out the power-magnet, and upon release of the key it will return to its normal position without energizing of the magnets.

With these objects in view and others my invention comprehends the construction, arrangement, and combination of parts, as hereinafter described and claimed.

Referring to the drawings representing an apparatus embodying my invention, Figure 1 is a front perspective view, certain parts being omitted. Fig. 2 is a vertical section through the middle of the machine. Fig. 3 is a similar view of a modification.

In the several views the characters of reference indicate the same part.

In a frame A are secured fulcrum-rods a a , that carry links a^2 a^3 , respectively, which latter support bent levers a^4 a^5 , each of the bent levers being supported by a link a^6 and a link a^8 , preferably arranged in parallelism. When

one of the bent levers a^4 is depressed, it will rock a type-bar a^5 through the medium of a lever a^6 and connecting-links a^7 a^8 .

A universal power-bar B extends between the links a^2 and a^3 and is supported at each end by an arm b, pivoted to the side plate of the machine. On each side of the links a^2 is pivoted an armature-lever c, carrying an armature c^2 , arranged to be attracted by one of a series of electromagnets c^3 , carried on a bar c^4 , of fiber or other suitable non-magnetic material. A retractile spring c^5 serves normally to retain the armature-lever c in the position shown and away from its operating magnet. The lower end of each of these armature-levers c has a hook-shaped foot or offset c^6 , that when the armature-lever is rocked through the influence of its controlling-magnet will be moved under the universal power-bar B; but when the magnet is again deenergized the retractile spring will move the foot away from its position of engagement with the power-bar.

On the base-plate is mounted an electromagnet D, having, preferably, two coils d^2 d^3 . An armature d^4 is suspended within range of the influence of the magnet D, being pivoted on a bar d^5 , that is carried by two levers d^6 d^7 , the latter being pivoted at d^8 to the side of the machine. The levers d^6 d^7 each have an arm d^9 , that is pivoted to one of the arms b. A retractile spring d^8 serves normally to retain the armature, the universal power-bar, and their connected parts in the position shown in the drawings and away from the electromagnet. Consequently when the electromagnet D is energized the armature will be attracted and rock the levers d^6 , the arms d^9 thereon, and then the pivoted arm b downward and also the universal power-bar B. Now should any of the selecting-magnets be energized, and thereby bring one of the feet c^6 under the universal power-bar, and thereupon the electromagnet D is energized, the power-bar will engage the hook c^6 in its downward movement, and thereby operate the corresponding type-bar through the aforesaid connecting members.

In my said application filed of even date herewith the armature-lever is retained in position by the selecting-magnet until the operating-magnet moves the power-bar to engage the hook on the lever by reason of the form of switch there employed. In the present invention I provide a latch E, pivoted on each of the links a^2 a^3 and resting upon the armature. When any of the armatures is attracted by its magnet, the latch will fall and bring its notched part e back of the armature, and thereby retain the armature-lever with its foot underneath the power-bar; but when the link a^2 and connected parts are carried down by the power-bar a stationary rod e^2 will strike the latch and arrest its movement, while the armature

continuing to descend will cause the latter to be discharged from the notched part of the latch.

For each of the selecting-magnets c^3 there is a three-terminal switch, preferably such as shown. In an insulating-block F is a metal bushing f, in which slides a stem f^2 , having a key f^3 . A plate f^4 carries the block F and also an insulating-block f^5 , that guides the end of the stem f, which latter has a coil-spring f^6 , that returns it when depressed. A spring-terminal f^7 is secured to the block F and is connected by suitable conductor with one terminal of a power-bar-operating magnet. Another spring-terminal f^8 is secured to the insulating-block f^5 and is connected by suitable conductor with one pole of the selecting-magnet. The other pole of the selecting-magnet and also the other pole of the power-magnet are connected by suitable conductor with one terminal of a source of electric current, such as a battery G. The other terminal of the battery is connected with the bushings f of all the keys.

When the key-stem is depressed a short distance, a cross-bar f^9 on the stem strikes a projection f^{10} on the terminal blade f^8 , thereby completing the circuit including the battery and the selecting-magnet. This will cause the armature of the selecting-magnet to be rocked and bring the hook-shaped foot of its lever under the power-bar B. At the same time the latch E will under its own weight have fallen so as to cause its notched end e back of the armature, and thus hold the armature-lever with its foot under the power-bar. A further movement of the key-stem will position the cross-bar f^9 beyond the projection of the terminal blade f^8 , thus cutting out the selecting-magnet and breaking the current; but the latch will not have become disengaged from the armature which it is then holding, but will tend to retain the armature-lever with its hook under the power-bar until disengaged therefrom in the manner already above described. Thereupon a further advancement of the key-stem will cause the bar f^9 to strike a projection f^{11} on the terminal f^7 , thus completing the circuit a second time, including the battery a second time and the power-bar magnet once or for first time, which will cause the power-bar to operate the type-bar, as hereinbefore set forth. A further depression of the key-stem will cause a pin f^{12} on the key-stem to move an insulating-lever f^{13} down and strike the bent end f^{14} of the terminal blade f^8 and move this blade so that its projection f^{10} will be out of range of engagement with the cross-bar f^9 , breaking the circuit through said terminal blade f^8 and permitting return to normal position of the operating parts independent of return of key. At the same time a pin f^{15} on the key-stem will cause an insulating-lever f^{16} to move the terminal blade f^7 so

that its projection f^{11} will be out of the range of movement of the cross-bar f^9 . Upon the key-stem being released it will be returned by the spring f^6 to its normal position, and the said levers f^{13} and f^{16} will hold the terminal blades f^7 f^8 against returning to their normal position, and thus prevent the cross-bar f^9 in ascending from engaging the projections on the terminal blades until the cross-bar shall have passed the projections. Thereupon in the continuation of the upward movement of the key-stem the pins f^{17} and f^{18} will strike the levers and raise them to their former positions and at the same time release the terminal blades.

In Fig. 3 I have shown another form of device for effecting the retaining of the selecting-pawl during any possible interval in the action of switching from one circuit to the other. In this construction the latches E and bar e are omitted and a permanently-magnetized armature c^3 is employed and which is constructed of a metal or alloy, such as Russia iron, that will retain the magnetism induced in it by the engaging electromagnet for a short period of time, sufficient for retaining it in proximity to the magnet with its lever-foot underneath the power-bar until the latter shall be actuated by its magnet and engage this foot and draw the lever downward, and thus remove the face of the armature from the field of attraction, as by drawing it down beyond the face of the magnet, which may, if desirable, be provided with a projecting face of suitable dimensions. Upon the release of the power-bar the retractile spring will withdraw the armature from the electromagnet.

The depression by the operator of the means (comprising the key-stem f^2) to select a particular type-bar and for creating a plurality of electric circuits actuates or projects it and its adjunctive parts to one of a plurality of operating or circuit-creating positions. The first circuit is established when the cross-bar f^9 impinges against the offset or projection f^{10} , arranged on the terminal f^8 , and the operation of this circuit positions the latch so that it can be operated by the power-bar when actuated. The additional continued projection of said key-stem f^2 positions the lever f^{13} to force the terminal outward, and thus break the circuit, as the latch has thereby been properly positioned. The further depression or projection of the key-stem places its adjunctive parts in a still different operating position—that is, it positions the cross-bar in engagement with the terminal f^{11} , and this establishes a circuit therethrough, and this energizes the power-bar magnet and actuates the power-bar to operate the latch and the type-bar. A further projection of said key-stem positions the lever f^{13} against that terminal and breaks the circuit there-through.

My invention is to be distinguished from other devices in the art in that in operation the parts are operated by a single circuit derived from a single source, which circuit is created through one terminal first to effect one operation, then interrupted through that circuit and simultaneously transmitted through a different terminal to effect a different operation, and so on, which circuit through the medium of my invention is under positive control, first directed as a distinct circuit to a selecting-magnet to position a movable part for actuation and then and in succession and as a distinct and positive operation directed as a different and distinct circuit to a power-bar-operating magnet, which in operating its said power-bar actuates said movable part which has previously been positioned for such actuation. My said invention is different from that constituting the subject-matter of my aforementioned pending application in that it includes a locking device which operates automatically to lock the movable part after being positioned until the power-bar has actuated it, which said locking device insures the proper positioning of the movable part until the power-bar has effected its function.

Having thus fully described my invention, what I claim as new, and desire to secure by Letters Patent of the United States, is—

1. The combination of a series of movable members, a universal power-bar, means for operating the power-bar, separate selecting means arranged to bring the movable members respectively into position to be engaged by the power-bar when the latter is actuated, a controlling means for each said movable members constructed to be actuated to a plurality of operating positions, and arranged, first, when actuated to its initial operating position, to move the selecting means into position for engagement with the power-bar, and thereupon, when actuated to a different operating position, to cause the power-bar to be actuated and operate the corresponding movable member, and means for retaining the said members in said positions until engaged by the power-bar, substantially as described.

2. The combination of a series of movable members, a universal power-bar, means for operating the power-bar, separate selecting means arranged to bring the movable members respectively into position to be engaged by the power-bar when the latter is actuated, and a controlling means for each said movable members constructed to be operated to a plurality of operating positions, and arranged, first, when actuated to its initial operating position, to move the selecting means into position for engagement with the power-bar, and then, when actuated to a different operating position, to cause the power-bar to be actuated and operate the corresponding

movable member, and a latch arranged to retain said members in said engaging position, substantially as described.

3. The combination of a series of movable members, a universal power-bar, means for operating the power-bar, separate selecting means arranged to bring the movable members respectively into position to be engaged by the power-bar when the latter is actuated, a controlling means for each said movable members constructed to be actuated to a plurality of operating positions, and arranged, first, when actuated to its initial operating position, to move the selecting means into position for engagement with the power-bar and then, when actuated to another operating position, cause the power-bar to be actuated and operate the corresponding movable member, a latch arranged to retain said members in said engaging position, and means for tripping said latch when the said member is actuated by said power-bar, substantially as described.

4. The combination of a series of movable members, a universal power-bar, an electromagnet for actuating the power-bar, an armature connected with each of said members, an electromagnet arranged to influence each of said armatures respectively and thereby bring them in position to be engaged and operated by the power-bar when actuated, and means arranged to retain the said members in said engaging position until engaged by the power-bar, and means arranged and constructed to be projected, in one direction, to a plurality of operating positions, and, first, when moved to its initial operating position, to energize one of the selecting-magnets and, then, when projected to a second operating position, to energize the power-bar magnet, substantially as described.

5. The combination of a series of movable members, a universal power-bar, means for actuating the power-bar, an armature connected with each of said members, an electromagnet arranged to influence each of said armatures respectively and thereby bring said members into position to be engaged and operated by the power-bar when actuated, and means for controlling the operation of the movable members constructed to be projected from a normally non-operating position to a plurality of operating positions and, when projected to its initial operating position, to energize one of said electromagnets and effect operation of one of said movable members, and, then, when further projected to a second operating position, to operate and position said power-bar, and a latch arranged to engage each of the said members and retain them in position to be engaged by the power-bar, substantially as described.

6. The combination of a series of movable members, a universal power-bar, means for actuating the power-bar, an armature connected with each of said members, an elec-

tromagnet arranged to influence each of said armatures respectively and thereby bring the members into position to be engaged and operated by the power-bar when actuated, a latch arranged to engage each of the said members and retain them in position to be engaged by the power-bar, and means for tripping the latches from the members when the same are operated by the power-bar, and means arranged to be projected from normal to a plurality of operating positions and constructed, when projected to its initial operating position, to energize the electromagnets and effect operation of said movable members and, then, when additionally projected, to effect engagement of the power-bar with said latch, substantially as described.

7. The combination of a series of type-bars, a series of operating-levers arranged to operate the type-bars respectively, a pair of links arranged to support each of said operating-levers, an armature-lever pivoted on one of each of said pairs of links, an armature on each of said armature-levers, an electromagnet arranged to operate each of said armatures, a universal power-bar, an armature connected with the power-bar, an electromagnet arranged to influence said latter armature and rock the power-bar, a lug on each of said armature-levers arranged to be moved into the path of movement of the power-bar when its armature is attracted by its engaging-magnet, means for first energizing each of the selecting-magnets, and then energizing the magnet to operate the power-bar, and a latch pivoted on one of each of said pairs of links and having a notched portion arranged to engage one of said armatures on said levers when moved into its said engaging position, substantially as described.

8. The combination of a series of type-bars, a series of operating-levers arranged to operate the type-bars respectively, a pair of links arranged to support each of said operating-levers, an armature-lever pivoted on one of each of said pairs of links, an armature on each of said armature-levers, an electromagnet arranged to operate each of said armatures, a universal power-bar, an armature connected with the power-bar, an electromagnet arranged to influence said latter armature and rock the power-bar, a lug on each of said armature-levers arranged to be moved into the path of movement of the power-bar when its armature is attracted by its engaging magnet, means for first energizing one of the selecting-magnets, means for then energizing the magnet to operate the power-bar, a latch pivoted on one of each of said pairs of links and having a notched portion arranged to engage one of said armatures on said levers when moved into its said engaging position, and a rod arranged to engage said latches when the members are moved by the power-bar and trip them from engagement with the

said armatures on said levers, substantially as described.

9. The combination, with a series of movable members, a power-bar, and a latch device, of means for operating the said movable members and power-bar, in succession, comprising a member having a single terminal thereon, and a member having a pair of terminals thereon, one of said members being movable to a plurality of operating positions relative to the other member, thereby to cause the terminals to engage, said terminals being so arranged on the members that, when the members are moved, the single terminal will first engage with one of the said terminals, and then after disengaging with said terminal will engage with the other terminal, substantially as described.

10. The combination, with a series of movable members, a power-bar, and a latch device, of means for operating the said movable members and power-bar, in succession, comprising a member having a single terminal thereon, and a member having a pair of terminals thereon, the former said member being movable to a plurality of operating positions to and from the other member, thereby to cause the terminals to engage, said terminals being so arranged on the members that, when the members impinge, the single terminal will first engage one of the said pair of terminals, and then disengage with said terminal, and then engage with the other terminal, substantially as described.

11. The combination, with a series of movable members, a power-bar, and a latch device, of means for operating the said movable members and power-bar, in succession, comprising a member having a single terminal thereon, and a member having a pair of terminals thereon, one of said members being movable to and from the other member, thereby to cause the terminals to engage, said terminals being so arranged on the members that, when the members are approximated, the said single terminal will first engage with one of the said pair of terminals and then, after disengaging with said terminal, will engage with the other terminal, and, upon a further movement in the same direction, will cause the latter terminals to disengage, and means for preventing the terminals from engaging upon the return movement of the movable member to its normal position, substantially as described.

12. The combination, with a series of movable members, a power-bar, and a latch device, of means for operating the said movable members and power-bar, in succession, comprising a movable stem, a bar on the stem, a flexible terminal blade having a lug thereon arranged to be engaged by the said bar on the advance of the stem, and to be disengaged by a continued movement of the stem, a second blade having a lug thereon arranged

to be engaged by the said bar on a further advance of the stem, after disengaging with said terminal, and means for moving the said terminal blades out of position of engagement with said lugs on a further movement of the stem and retaining them in said position until the stem is returned and the bar passed beyond said lugs, substantially as described.

13. The combination, with a series of movable members, a power-bar, and a latch device, of means for operating the said movable members and power-bar, in succession, comprising a movable stem, a bar on the stem, a flexible terminal blade having a lug thereon arranged to be engaged by the said bar on the advance of the stem, and to be disengaged by a continued movement of the stem, a second blade having a lug thereon arranged to be engaged by the said bar on a further advance of the stem, after disengaging with said terminal, means for moving the said terminal blades out of position of engagement with said lugs on a further movement of the stem and retaining them in said position until the stem is returned and the bar passed beyond said lugs, and means for automatically releasing said terminal blades and permitting them to return to their normal position.

14. The combination, with a series of movable members, a power-bar, and a latch device, of means for operating the said movable members and power-bar, in succession, comprising a movable stem, a bar on the stem, a flexible terminal blade having a lug thereon arranged to be engaged by the said bar on the advance of the stem, and to be disengaged by a further advance of the stem, a second blade having a lug thereon arranged to be engaged by said bar on a further advance of the stem after disengaging with said terminal, a pair of levers arranged to be engaged by the stem on a further advance and each move one of said blades out of position of engagement with the lugs on the blades, and means on the stem for moving said levers to release said blades on the return movement of the stem after the said bar has passed the position of engagement with the lugs, substantially as described.

15. The combination, with a series of movable members, a power-bar, and a latch device, of means for operating the said movable members and power-bar, in succession, comprising a supporting-plate, a pair of insulating-blocks secured to the plate, a stem arranged to slide in said plates, a spring arranged to retain the stem in one position a bar on said stem, an elastic terminal blade secured to one of said blocks, a lug on said blade arranged to engage the bar when the stem is advanced, an elastic terminal blade secured to the other blade, a lug on the second blade arranged to engage the said bar on

- a further advance of the stem after the bar has disengaged with said lug, said second terminal being arranged to disengage the bar on a further advance of the stem, an insulating-
 5 lever pivoted on the plate, a stop-pin on the stem arranged to strike the said lever on said latter advance of the stem and thereby to cause the lever to move the first-mentioned blade out of position of engagement with said bar, a second insulating-lever pivoted on the supporting-plate, a pin on the stem arranged to cause second lever to move the second terminal blade out of position of engagement with the bar on said latter movement of the
 10 stem, said levers being arranged to retain the blades in said positions until the stem and bar are returned by said spring past the positions of engagement with said lugs, and pins on the stem arranged to move the said levers on the further return movement of the stem and thereby cause them to disengage the said terminals, substantially as described.
 15 16. The combination of a series of movable members, a universal power-bar, an electromagnet arranged to operate the power-bar, a separate selecting-electromagnet for each said movable member, a separate means for energizing each selecting-magnet, said latter means being also arranged to be projected from normal to a plurality of operating positions and constructed, when projected to its first operating position to energize the selecting-magnet, then when additionally projected to a second operating position to deenergize the selecting-magnet, and thereupon when projected to a third operating position to energize the power-bar-operating magnet, substantially as described.
 20 17. The combination of a series of type-bars, a series of keys corresponding to the type-bars, a universal power-bar, electromagnets arranged to operate the power-bar, means for causing the operation of any of said keys and arranged to be projected from normal to a plurality of operating positions, and constructed, when projected to its initial operating position, first to energize its corresponding selecting-magnet, then when additionally projected to a second operating position to deenergize the selecting-magnet, and thereupon when projected to a third operating position to energize the power-bar magnet, substantially as described.
 25 18. The combination of a series of movable

members, a power-bar, and a latch device, of means for creating and directing a plurality of electrical circuits, from a single source, connections between said source of electricity and said movable members and power-bar, means constructed to be projected from normal to a plurality of circuit-creating positions for effecting, first, a distinct circuit from said single current to said movable members to position them for actuation without simultaneously effecting a circuit also to said bar and, then, effecting a separate and distinct circuit from the same single current, to the power-bar, without continuance of said first circuit to said movable member, for actuating said movable part, and, finally, discontinuing said second circuit, to permit the parts to resume their normal position, substantially as described.

19. The combination of members, a plurality of terminals movable with relation to each other and carried by the said members, a plurality of selecting-magnets, a plurality of members controlled through said selecting-magnets, a universal power-bar, an electromagnet arranged to operate the power-bar, means for first energizing a predetermined one of the selecting-magnets, means for retaining the controlled member when selected, means for energizing the power-bar magnet, means for deenergizing said magnets to permit return of the parts independent of the return of the movable terminals, substantially as described.

20. The combination of a series of movable members, a universal power-bar, an electromagnet arranged to operate the power-bar, a separate selecting-electromagnet for positioning each movable member, means for retaining each movable member in such position, separate means for energizing each selecting-magnet and arranged to operate, first to energize the selecting-magnet, then to deenergize the selecting-magnet, then to energize the power-bar-operating magnet, and finally to deenergize said power-bar magnet to permit independent return of the parts to normal position, substantially as described.

In testimony whereof I affix my signature in the presence of two subscribing witnesses.
